DROP BOMB

Thomas E. Murray, Brooklyn, and George H. Phelps, Floral Park, N. Y.; said Phelps assignor to Murray Manufacturing Corporation, Brooklyn, N. Y., a corporation of New York, and said Murray assignor to Yarrum, Inc., Brooklyn, N. Y., a corporation of New York

Application December 6, 1939, Serial No. 307,728

6 Claims. (Cl. 29—1.21)

The invention herein disclosed relates to a drop bomb and to a method for making such a bomb.

A primary object of the invention is to provide a drop bomb that is readily manufactured and suitable for rapid, quantity production. Another object of the invention is to provide a construction of a bomb which lends itself to producing the major portion of the bomb from plate steel. A further object of the invention is to provide a bomb that may be constructed from plate and which has uniformity of strength throughout.

In accordance with the invention there is provided a drop bomb that comprises three portions, a body portion, a thicker intermediate portion and a nose portion. The body portion and thicker intermediate portion are made up of similar longitudinal sections drawn from plate which plate comprises two pieces of plate of different thicknesses united in edge to edge relation. The sections are united to form the body and intermediate portion of the bomb and the nose portion is united to the end of the intermediate portion.

Such a bomb is made in accordance with the method of the invention by stamping flat blanks representing the development in a plane surface of sections of the body and intermediate portions of the bomb, each blank comprising two pieces of plate of different thicknesses united in edge to edge relation by a coalescence and ingrainning of the metal. The blanks so formed are drawn to form sections which when united form the body and intermediate portions of the bomb and the drawn sections are united by electrically effecting a unification of the metal at the registering edges. Thereafter, the formed nose portion is united to the end of the intermediate portion in a circumferential unification of the metal at the circular edges of the intermediate and nose portions.

The blanks and drawn sections formed in the intermediate stages of the method of this invention and a bomb embodying the invention are illustrated in the accompanying drawings in which:

Fig. 1 is a side elevation, partly in section, of a bomb;

Fig. 2 illustrates a plate in plan and edge elevation;

Fig. 3 illustrates another plate in plan and edge elevation;

Fig. 4 illustrates a blank in plan and edge elevation; and

Fig. 5 illustrates a plan and end view of a drawn section.

The bomb illustrated in the drawings includes three portions, a body portion 1, an intermediate tapering portion 2 having a thicker wall than the wall of the body portion 1 and a nose portion

3. The body portion is cylindrical throughout the greater portion of its length, tapering at its rear end 1a to the rear or tail end of the bomb. The body portion and the intermediate portion together are made up of two similar, longitudinally divided half-sections welded at their registering edges. The nose portion 3 of the bomb which may be and preferably is made of high strength steel, is united with the forward end of the intermediate portion in edge to edge relation.

In constructing the bomb, a plate 4, such as that illustrated in Fig. 2, of requisite thickness to form the intermediate portion 2 of the bomb, is reduced in thickness along one edge to form an edge portion 5 of the same thickness as the plate to be used for the body portion 1 of the bomb. Fig. 2 illustrates a plate 6 for the body portion of the bomb. This plate 6 is of uniform thickness and the two plates are brought together in edge to edge relation with the edge portion 5 of the plate 4 abutting against the end edge of the plate 6. In this relation a very high electrical current is caused to pass between the two plates and at the same time the plates are pressed together. In this manner the metal of the plates, at the joining edges, is caused to embed one within the other and a coalescence and ingrainning of the metal is effected. The burr formed in the welding of the two plates may be removed.

The development in a plane surface of a longitudinally divided half-section of the intermediate portion 2 of the bomb is indicated on the plate 4 by the broken lines 7. Similarly, the development in a plane surface of a longitudinally divided half-section of the body portion 1 of the bomb is indicated by the broken lines 8 on the plate 6 in Fig. 2. These plates may be stamped along the broken lines either before or after the plates are joined together. In the event the plates are stamped prior to welding, two blanks are formed and these are welded together in edge to edge relation. If the weld be effected first, a single blank 9 shown in full lines in Fig. 4 is stamped from the plate. The broken line 10 of Fig. 4 indicate the outline of the plate from which the blank 9 is stamped.

In either event, the welded blank is flat. This condition greatly facilitates, and enhances the accuracy of, inspection of the weld. In addition, in the subsequent drawing operation, hereinafter described, the weld is automatically tested by the drawing operation, and the metal in the region of the weld is worked.

The blank 9 is placed between suitable dies and drawn to the concave section 11 illustrated in Fig. 5. This section constitutes a longitudinally divided half-section of the body and intermediate portions of the shell. It will be noted that the blank is drawn so that the shoulder 12 formed

by the change in thickness of the metal is on the inside of the section 11. A smooth unbroken exterior surface is thus attained. Such a smooth unbroken surface on the exterior of the bomb and a smooth unbroken interior surface may be attained by reducing the joining edge of the plate 4 in a smooth wedge shape. This may be done by removing all of the metal necessary to be removed from one side of the plate or removing part from each side.

Two such sections 11 form the intermediate and body portion of the bomb. These sections are interchangeable and the two sections are laid in complementarily recessed electrodes with their longitudinal edges engaging and a unification of the metal at the registering edges is effected in the manner heretofore described. To the end of the intermediate portion, the nose portion is welded. The nose portion is a solid piece of metal and it is united to the intermediate portion in a circumferential weld in the manner described. The nose portion thus forms a securing element between the longitudinally divided half-sections of the bomb.

From the foregoing description of the bomb of this invention and the method for making the bomb, it will be apparent that it is possible to use metals of different properties in the different sections of the bomb. In this way, the best possible characteristics for the bomb as a whole may be attained at minimum expense. As an example, the bomb may consist of a high alloy steel nose, an intermediate section of low alloy steel, and a body portion of plain low carbon steel. Likewise the bomb is suitable for manufacture, in accordance with the method of the invention, in large quantities with available equipment.

It will be obvious that various changes may be made by those skilled in the art in the steps of the method and the details of the bomb disclosed in the drawings and described in detail above within the principle and scope of the invention as expressed in the appended claims.

We claim:

1. The method of making a drop bomb having a body portion, a thicker tapering intermediate portion and a nose portion, which method includes the steps of stamping flat blanks representing the development in a plane surface of a section of the body and intermediate portions of the bomb, each blank comprising two pieces of plate of different thickness united in edge to edge relation to form a smooth unbroken surface on one side by a coalescence and ingrainning of the metal, drawing the blanks to form sections which when united form the body and intermediate portions of the bomb, uniting the drawn sections by electrically effecting a unification of the metal at the registering edges, and electrically uniting a formed nose portion to the end of the intermediate portion in a circumferential unification of the metal at the circular edges of the intermediate and nose portions.

2. The method of making a drop bomb having a body portion, a thicker tapering intermediate portion and a nose portion, which method includes stamping a blank from uniform plate of one thickness, each blank representing a development in a plane surface of a section of the body of the bomb, stamping blanks from uniform plate of a greater thickness, each blank representing a development in a plane surface of a section of the intermediate portion of the bomb, uniting the body and intermediate blank sections in edge to edge relation by a coalescence and ingrainning

of the metal, drawing the blanks to form sections which when united form the body and intermediate portions of the bomb, uniting the drawn sections by electrically effecting a unification of the metal at the registering edges of the sections, and electrically uniting a formed nose portion to the end of the intermediate portion in a circumferential unification of the circular edges of the intermediate and nose portions.

3. The method of making a drop bomb having a body portion, a thicker tapering intermediate portion and a nose portion, which method includes reducing the edge thickness of one to the thickness of another plate of lesser thickness, uniting the plates in edge to edge relation by a coalescence and ingrainning of the metal, stamping blanks from the united plate, each blank representing a development in a plane surface of a section of the body and intermediate portions, drawing the blanks to form sections which when united form the body and intermediate portions of the bomb, uniting the drawn sections by electrically effecting a unification of the metal at the registering edges of the sections, and electrically uniting a formed nose portion to the end of the intermediate portion in circumferential unification of the metal at the circular edges of the intermediate and nose portions.

4. The method of making a drop bomb having a body portion, a thicker tapering intermediate portion and a nose portion, which method includes reducing the edge thickness of one to the thickness of another plate of lesser thickness, uniting the plates in edge to edge relation by a coalescence and ingrainning of the metal, stamping blanks from the united plate, each blank representing a development in a plane surface of a semi-longitudinally divided section of the body and intermediate portions, uniting the drawn sections by electrically effecting a unification of the metal at the registering edges of the sections, and electrically uniting a formed nose portion to the end of the intermediate portion in circumferential unification of the metal at the circular edges of the intermediate and nose portions.

5. The method of making a drop bomb having a body portion, a thicker tapering intermediate portion and a nose portion, which method includes the steps of forming sections of the body portion and the intermediate portion from plate of different thicknesses, uniting these formed sections by electrically effecting a unification of the metal at the registering edges, and electrically uniting a formed nose portion to the end of the intermediate portion in a circumferential unification of the metal at the circular edges of the intermediate and nose portions.

6. The method of making a drop bomb having a body portion, a thicker tapering intermediate portion and a nose portion, which method includes the steps of forming sections of the body and intermediate portions from plate of different thicknesses including drawing plate to form longitudinally divided sections of the said portions, uniting the edges of the sections of such portions to form the said portions by electrically effecting a unification of the metal at the edges of the sections, and electrically effecting a unification of separately formed portions in a circumferential unification of the metal at the circular edge of the portions.
